UNITED STATES PATENT OFFICE.

NEAL ALLEN, OF PITTSBURG, KANSAS.

MACHINE FOR PRODUCING ORNAMENTED BRICK.

1,230,362.

Specification of Letters Patent. Patented June 19, 1917.

Application filed January 23, 1917. Serial No. 143,993.

To all whom it may concern:

Be it known that I, NEAL ALLEN, a citizen of the United States of America, and a resident of Pittsburg, Crawford county, Kansas, have invented certain new, novel, and useful Improvements in Machines for Producing Ornamented Brick, of which the following is a specification.

My invention relates to machines for producing building bricks, with one or more ornamented edges, and is especially adapted to use with that type of brick-making machines which force a continuous column of plastic clay through proper sizing-dies, over a table to the cutting apparatus, where it is cut into brick forms.

The column is a parallelogram in cross section and its four faces are of a smooth, glossy, monotonous sameness, which become the four edges or smaller faces of the brick when cut into forms, and the object of my invention is to break up, mat and roughen, in irregular eccentric figures, one or more faces of said column, with small added expense and without interruption of the brick-making process.

Referring to the accompanying drawings, Figure 1, is a side view of a section of the column of clay and its supporting table, my invention mounted upon and attached thereto, between the column-forming dies, at the right and the brick cutting apparatus, at the left (not shown in the drawing).

Fig. 2 is an end view, showing column in cross-section with rod in horizontal position, partly buried in the upper face thereof.

Fig. 3 shows a brick, with ornamentation of two of its faces, the result of the roughing rod action; *w*, *w*, being the relief-like effect and *x*, *x*, being the roughened, matted, tangled portion.

Similar letters of reference indicate similar parts throughout the several figures, in which—

b is the roller or smoother, rotated by the continuous forward movement of the clay column, *s*; *e* is the frame, provided with bearings for shaft *c*, upon which roller *b* is mounted; frame at rear is secured by hinge-shaft *f*, mounted in bearings provided in top of supporting column *g*; the lower end of which is secured to the column table base, *r*; *k* is pulley fixed on end of rod *m*, by which, with belt to main or line shaft (or gears if preferred) rod *m* is rotated; *q*, a support, with lower end secured to table

base *r*, extends diagonally upward and backward, is furnished at its outward extremity, with bearings for rod *m*; a slot is formed at proper point in *q* for insertion of adjusting bar *n*; *i* is weight-frame, showing weightbox *h* and is adjustably secured by slot in forward end, through which bar *n* passes, held by adjusting nut *o*; and fulcrumed on hub of rod *m*, at *l*; *p* is adjusting nut on bar *n*, for regulating depth of rod *m*, penetrating clay column face; *s* is the clay column; *u* shows the outline of broken-up, roughened face of column; *t* is table top; *v*, *v*, *v*, are rollers upon which clay column moves to cutting apparatus; *d* is the outer face of roller or smoother, *b*; *a* is a weight to give pressure to roller *b*.

Parts designated *e*, *f*, *g*, *i*, *l*, *p*, *q*, *n*, are duplicates of similar parts unseen in the drawings.

In operation, the column of plastic clay, *s*, is forced through the brick-sizing dies, toward the cutting apparatus on the left. The rod, formed of suitable material, of proper length to cross the column face and hold pulley and bearings, not less than five eighth inch in diameter, set at right angle to face of column *s* and contacting with it, is rotated, by belt and pulley *k*, in reverse direction to the course of the column, at about 40 revolutions per minute. The rod is set, by means of the adjusting nut *p*, to bury itself about one thirty second of an inch into the face of the column it is in contact with.

The frame *i*, with its weight *h* secured by slot on bar *n* with adjusting nut, *o* and fulcrumed on hub *l*, is for regulating pressure of roughing rod *m* upon clay column surface. The depth to which rod *m* should enter clay column face is regulated by adjusting nut *p*, which may raise or lower *q*, which holds rod *m* in bearings, as desired. Springs or other pressure devices may be used instead of weights.

The forward continuous moving column *s* rotates the pulley *b*, its outer surface, *d*, contacting with and smoothing the jagged points of the broken surface of the column, and restoring it to its original outline.

The rod *m*, revolving reversely to the direction of the slower moving column *s*, wraps about itself the sticky, pasty, plastic material of the column and continuously unloads upon the already-roughened, broken surface, passing forward, leaving it in matted, irregular, eccentric, relief-like

and uniquely ornamental figures, ever changing and never duplicated.

The jagged points are reduced and outline of column restored as it passes under roller *b*, cutting apparatus, where it is cut into brick forms, retaining the ornamental figures produced by the action of the rod *m*. The face of roller may be provided with a textile covering or be cordage wound and further ornament the roughened surfaces, 10 by leaving the imprint thereof on the contacted surfaces.

While only one column surface is shown in drawings and herein described, a horizontal and a vertical rod *m*, may be used at the same time, with proper following rollers 15 or smoothers, which will ornament two faces simultaneously.

Having described my invention, what I 20 claim as new and desire to secure by Letters Patent, is

1. In a machine for producing eccentric irregular figures upon the smooth face of a column of plastic clay as it moves forward 25 from the dies of a brick-making machine, a round rod of proper dimensions, mounted in bearings supported by a suitable frame attached to column table, means for rotating said rod reversely to the direction of 30 the continuously moving column of plastic

clay, said rod arranged to contact with and across a face of said clay column, means for regulating the pressure of said rod against said face, means for smoothing said disturbed face to original outline, as specified 35 and described.

2. In a machine for ornamenting a face of a continuously moving column of plastic clay as described, by matting and breaking up said face, a rotating rod, arranged to 40 contact with and across the smooth face of the said continuously forward moving column, said rod being rotated reversely to the direction of the said moving column, means for regulating the pressure of said 45 rod against said moving column, means for smoothing the lacerated and roughened surface, means for imparting a textile or cordage-like effect to the raised portions of the relief-like sections of the ornamented face, as 50 specified and set forth.

In testimony that I claim the above, I have hereunto subscribed my name in the presence of two witnesses this 18th day of January, 1917.

NEAL ALLEN.
